CONVERTIBLE GARMENT

Sam Bernard Hyman, Los Angeles, Calif.

Application February 7, 1934, Serial No. 710,072

2 Claims. (Cl. 2-95)

The invention relates to improvements in convertible garments and has for its primary object the provision of an improved construction of this character so constructed and arranged that it 5 may be readily and advantageously worn as a coat member or as a combination sweater and coat member.

Other objects will appear hereinafter.

The invention consists in the combinations and 10 arrangements of parts hereinafter described and claimed.

The invention will be best understood by reference to the accompanying drawing forming a part of this specification and in which

15 Fig. 1 is a front perspective view showing the garment adjusted for use as a combination sweater and coat member;

Fig. 2, the same garment converted into a simple coat member having a double back;

20 Fig. 3, a vertical medial section of the garment in the condition shown in Fig. 1;

Fig. 4, a vertical section of the garment in the condition shown in Fig. 2;

25 Fig. 5, an enlarged horizontal section of the garment taken substantially on line 5-5 of Fig. 3; and

Fig. 6, an enlarged horizontal section of the garment taken substantially on line 6-6 of Fig. 4.

The embodiment of the invention illustrated 30 in the drawing comprises an outer coat member 10 having sleeves 11 and usual buttons 12 and button holes 13 at the front, said coat member being preferably formed of woven woolen material such as is usually employed in sweater coats. Secured within the coat member 10 is a sweater 35 element 14 preferably of the same material as coat 11 and secured thereto at opposite sides along the vertical medial lines 15. The element 14 is provided at its top central portion with the forward portion of a neck opening 16 and at opposite sides thereof with arm hole portions 17 registering with the arm holes 18 of the coat 10 as shown. As will be noted in Fig. 6 of the drawing, the element 14 has a lateral extent substantially equal to the extent of the rear portion of said body member lying between the places of attachment thereto so as to be capable of resting smoothly against the rear of the body member or to extend outwardly to form a covering for the front body portion of the wearer.

50 By this arrangement a convertible garment is provided in which the sweater element 14 may

be readily folded against the back thereof as indicated in Figs. 2, 4 and 6, so that the garment may be thus worn as a sweater coat. When so worn the back thereof is constituted of a double thickness of material which reinforces the same 5 and affords added warmth at the back of the wearer when desired. Also, when desired, the sweater element 14 may be extended forwardly as shown in Figs. 1, 3 and 5, and the garment thus converted into a slip-on combined sweater coat 10 as indicated. When thus employed the sweater element 14 will appear as the front of a slip-on sweater worn under the outer coat member 10, the back of the coat member co-operating there-with to constitute a slip-on sweater. 15

In this way a convertible garment is provided which may be worn either as a sweater coat or as a combined sweater and coat which is of simple construction, attractive in appearance and capable of economical production. 20

While I have illustrated and described the preferred form of construction for carrying the invention into effect, this is capable of variation and modification without departing from the spirit of the invention. I therefore do not wish 25 to be limited to the precise details disclosed, but would desire to avail myself of such variations and modifications as fall within the scope of the appended claims.

I claim:

1. A garment of the class described comprising a body member arranged to encompass the body of the wearer; and an adjustable continuous unbroken element secured in said body at opposite sides thereof and adapted and arranged to co- 35 operate with the rear portion of said body to constitute a slip-on sweater-like garment or to be arranged against the rear of said body member to constitute a double back therefor.

2. A garment of the class described comprising 40 a body member arranged to encompass the body of the wearer; and an adjustable continuous unbroken element secured in said body member at opposite sides thereof and of a lateral extent substantially equal to the extent of the rear portion 45 of said body member lying between the place of attachment thereto, so as to be capable of resting smoothly against the rear of the body member or to extend outwardly to form a covering for the front body portion of the wearer. 50

SAM BERNARD HYMAN.
